WILLIAM A. WINTER, OF EAST ORANGE, NEW JERSEY, AND ROBERT KLETT, OF NEW YORK, N. Y., ASSIGNORS TO KNY-SCHEERER COMPANY.

MECHANICAL TIME-SWITCH FOR X-RAY SYSTEMS.

1,129,263.

Specification of Letters Patent. Patented Feb. 23, 1915.

Application filed March 27, 1914. Serial No. 827,620.

To all whom it may concern:

Be it known that we, WILLIAM A. WINTER, a citizen of the United States, and a resident of East Orange, New Jersey, and ROBERT KLETT, a resident of 1680 Clay avenue, in the borough of the Bronx, New York, N. Y., a subject of the Emperor of Germany, have invented certain new and useful Improvements in Mechanical Time-Switches for X-Ray Systems, as set forth in the following specification.

This invention relates to time switches and especially to those of a type serviceable in timing the length of exposure in X-ray work. Much more accurate and reliable results in X-ray photography can be obtained by exposures throughout definite time intervals, which are accurately measured instead of throughout time intervals subject to guess.

It is an object of the present invention to provide a time switch fulfilling the needs in connection with X-ray work and providing for the closing of the circuit at the will of the operator and the breaking of the said circuit after a predetermined time interval, which may be varied at the will of the operator.

In furtherance of the general object of the invention there is contemplated a coöperating pointer and scale divided into time graduations, through the medium of which the time switch may be set to fix the duration of circuit closure to the time interval designated on the scale by the pointer. In the makeup of the mechanism there is also provision for setting the time switch for the predetermined time interval independently of the means actually employed for closing the circuit.

The objects and general advantages of the invention will be set forth more fully in the following claims, which claims should be read in connection with the illustrative embodiment of the invention described in the following specification and shown in the accompanying drawings which form a part of this application in which like characters designate corresponding parts throughout the several figures and in which:—

Figure 1 is a front elevation of the switch; Fig. 2 is a side elevation of the same; Fig. 3 is a vertical section along the line III—III of Fig. 2; and Fig. 4 is a similar section along the line IV—IV of Fig. 2; and Fig. 5

is an enlarged section through the line V—V of Fig. 1.

Referring now more in detail to the drawings of the illustrative embodiment, a base is indicated by A in the form of a slab of suitable insulating material such as slate or transite. Four spacing legs B suitably secured to the base A serve to mount a face plate C, the face plate being shown secured to the legs B by screw D. A dial E is formed on the face plate C and is graduated into suitable time intervals. The graduations shown are from 0.1 to 2.0 seconds in space of one-tenth second. The pointer F, operated by the handle 1 is mounted to rotate about the stud 2, concentric with the dial E. Through the medium of the stud 2, which works in the bearing 3 mounted on the face plate C, the pointer F is rigidly connected with the forked arm 4 located back of the face plate C and constrained to rotate commensurately with the pointer F.

Mounted upon the base A in a suitable manner is a frame G which serves as the mounting for a gear train H. The gear train H is driven by the spring motor I, the tension of which may be adjusted through the medium of the winding spindle J upon which the spring I is wound and which carries a ratchet 4' coöperating with the pawl 5, fixed to the gear 6. The gear 6 meshes with the pinion 7 fastened on the shaft 8 and through the medium of the shaft 8 rigidly connected to drive the gear 9. The gear 9 drives an escapement 10 through the medium of the pinion 11. Suitably keyed to a forward extension of the shaft 8 is a disk K provided with notches L at its periphery, and serving as a time element of the switch.

Mounted on the forward portion 13 of the frame G through the medium of the pivot hinge 14 is a bell crank lever 15, the right angular offset arm 16 of which is in the path of the pin 17 fixed to the time element or notched disk K. The pressure of the pin 17 against the arm 16 is sufficient to hold the end of the arm 16 against the stop 18 and to overcome the tension of the spring 19, which tends to close the contact 20 against the contact 21 so that their silver tips 22 and 23 make electrical connection one with another. The contact 21 is electrically connected with the terminal post 24 which is

suitably insulated from the metallic frame G. These parts 15, 16, 19, 20, 21 and 24 constitute a circuit closer M.

An electrically conductive post 25 has pivoted to it the lever 26 which is normally spring operated by the tension spring 27 to force the trigger 28 against the rear face of the notched disk K or into one of the notches L. Fixed also to the same end of the lever 26 is a silver contact disk 29 which coöperates with the similar contact disk 30 electrically connected with the terminal post 31 which is mounted upon but insulated from the plate 13 of the frame G. Laterally offset from the lever arm 26 is a lip 32 carrying at its end a stud 33 serving as a guide for the compression spring 34 and pierced by the stem 35 of the push button 36. The rear end of the stem 35 is upset into a head 37 to retain the parts. A second push button N has its stem 40 bearing in the bushing 41 which is mounted in the face plate E. Fixed to the rear end of the stem 40 is a disk 42 engaging with the push button 36. The lever 26, contact 29, contact 30 and terminal post 31 constitute a second circuit closer which is electrically connected with the first circuit closer M through the medium of the frame G to which the post 25 is secured.

Connection between the operating handle 1 and the notched disk K is provided through the medium of the stud P which is fixed to the disk K and is straddled by the forked end of the arm 4.

With all parts in normal position and the pointer F pointing to zero the circuit between the two terminal posts 24 and 31 is broken at two points, *i. e.*, at each of the open circuit closers M and O. The rotation of the pointer F in a clockwise direction causes the disk K to travel in a similar direction. The stud 17 is withdrawn from the lever arm whereupon the circuit closer M closes. The trigger 28 is progressively pressed into the notches L which correspond to the graduations on the dial E, until no further rotation is given to the pointer F by the operator. Thereupon the trigger 28 comes to rest in one of the notches L in which position it is held by the spring 27. The switch is now set to maintain a circuit closure for the predetermined interval at the will of the operator. The rear walls of the notches L form detents which coöperate with the trigger 28 to hold the time element set ready to be released by pressure on the push button N.

When it is desired actually to make the exposure the push button N is pushed in. The spring 34 is designed to yield considerably before disengagement of trigger 28 from the disk is effected. As soon as the trigger 28 disengages the disk K the spring 34 causes an instantaneous closure between the

contacts 29 and 30 and so that the circuit closer O is held closed as long as the push button N is pressed in by the operator.

The second and final closure in the circuit through the switch is therefore effected contemporaneously with the release of the time element K. When the time element has completed its predetermined travel the pin 17, striking the arm 16, opens the first circuit closer M to break the circuit and terminate the period of exposure. As soon as the push button N is released the second opening in the operating circuit is again made. By the reason of the two openings at the two circuit closures in the exposure circuit, premature exposures are prevented and more efficient electrical control is obtained.

The clockwise rotation of the disk K drives the gear train H against the force of the spring I and when the disk K is released the spring I returns the disk K to its normal position. The escapement 10 serves as a governor more accurately to control the timing of the moving parts.

What is claimed and what is desired to be secured by United States Letters Patent is:

1. In a time-switch, two normally open circuit-closers in series connection; a movable time element; means for setting said time element to operate, when released, through any one of various time-intervals, comprising a series of detents and an engaging trigger, each detent corresponding to one of said various time-intervals; means operable upon the setting of said time element for closing one of said circuit-closers; means for simultaneously releasing said time-element and closing said second circuit closer; and means for opening said first circuit closer after a predetermined time interval through the medium of said time element.

2. In a time-switch, a movable time element capable of being set to travel, when released, through any one of various predetermined time intervals and having a series of detents, one for each time-interval; an electric circuit; means for simultaneously releasing said time element and closing said circuit; and means automatically operated at the completion of the movement of said time element for opening said circuit.

3. In a time-switch, a rotary time-element; a motor for rotating said time element; a governor for controlling the rate of rotation of said time-element; a graduated dial for indicating the timed displacement of said time-element; a trigger for holding said time-element set in displacement in any one of variously timed positions; an electric circuit normally open; means operating upon the actuation of said trigger in releasing said time element to close said circuit; and means automatically operated upon the

rotation of said time-element to open said circuit.

4. In a time-switch, a rotary time-element; a motor for rotating said time element; a governor for controlling the rate of rotation of said time-element; a graduated dial for indicating the timed displacement of said time-element; a trigger for holding said time-element set in displacement in any one of variously timed positions; an electric circuit normally open; means operating upon the actuation of said trigger in releasing said time element to close said circuit; and means automatically operated upon the rotation of said time-element to open said circuit at a second point.

5. In an adjustable time switch, an escapement gear train; a spring motor for driving said gear train; a notched disk mechanically connected with said gear train and operable to place said spring motor under tension when rotated in one direction and when released to rotate with said gear train; a pointer and graduated dial indicating the rotary position of said disk; releasable means cooperating with said notched disk for holding it against rotation in any one of various positions corresponding to said notches; and circuit controlling means operable upon the complete rotation of said disk by said spring motor.

6. An adjustable time-switch for closing a circuit at the instant of actuation and for opening it at the expiration of accurately

measured small time-intervals comprising two normally open circuit-closers; a time-measurer; a means for causing one circuit-closer to close and for predetermining among any one of various time-intervals the time interval throughout which said circuit is to be closed, comprising a trigger for gripping said time-measurer and holding it set for operation throughout the particular predetermined time-interval; means for releasing said trigger and for simultaneously closing said second circuit-closer; and means operated upon the completion of the predetermined time-interval for opening said first circuit-closer.

7. In a time-switch a time-element; means tending to drive said time-element; one or more detents each corresponding to a distinct time-interval; a trigger for engaging one of said detents at a time; a switch arm associated with said trigger; and means for giving a quick movement to said arm and trigger comprising a manual actuator, and resilient means interposed between said actuator and said arm.

In witness whereof, we have signed our names to this specification, in the presence of two subscribing witnesses.
